CHANUKAH TABLE ORNAMENT OR SIMILAR ARTICLE

Sara Rae Naimon, Milwaukee, Wis.

Application March 12, 1956, Serial No. 40,566

Term of patent 14 years

(Cl. D29—23)

Fig. 1.

Fig. 2.

Fig. 3.

Fig. 4.

Fig. 5.

I claim:

The ornamental design for a Chanukah table ornament or similar article, as shown.
